CLAIM

The ornamental design for a holder for a portable electronic device, design as shown and described.

DESCRIPTION

FIG. 1 is a perspective view of a holder for a portable electronic device showing the subject design;

FIG. 2 is a front view of the holder for a portable electronic device shown in FIG. 1;

FIG. 3 is a back view of the holder for a portable electronic device shown in FIG. 1;

FIG. 4 is a left side view of the holder for a portable electronic device shown in FIG. 1;

FIG. 5 is a right side view of the holder for a portable electronic device shown in FIG. 1;

FIG. 6 is a top view of the holder for a portable electronic device shown in FIG. 1;

FIG. 7 is a bottom view of the holder for a portable electronic device shown in FIG. 1;

FIG. 8 is a perspective view of a variant of the holder for a portable electronic device shown in FIG. 1;

FIG. 9 is a front view of the holder for a portable electronic device shown in FIG. 8;

FIG. 10 is a back view of the holder for a portable electronic device shown in FIG. 8;

FIG. 11 is a left side view of the holder for a portable electronic device shown in FIG. 8;

FIG. 12 is a right side view of the holder for a portable electronic device shown in FIG. 8;

FIG. 13 is a top view of the holder for a portable electronic device shown in FIG. 8; and,

FIG. 14 is a bottom view of the holder for a portable electronic device shown in FIG. 8.
